CLAIM

The ornamental design for a writing instrument, as shown and described.

DESCRIPTION

FIG. 1 is a rear and left side perspective view showing my new design for a writing instrument;

FIG. 2 is a front and left side perspective view of the writing instrument of FIG. 1;

FIG. 3 is a side view of the writing instrument of FIG. 1, the opposite side being a mirror image thereof;

FIG. 4 is a front view of the writing instrument of FIG. 1;

FIG. 5 is a rear view of the writing instrument of FIG. 1;

FIG. 6 is a top plan view of the writing instrument of FIG. 1;

FIG. 7 is a bottom plan view of the writing instrument of FIG. 1;

FIG. 8 is an exploded front and left side perspective view showing the writing instrument and cap of FIG. 1 in an open condition;

FIG. 9 is an exploded rear and left side perspective view of the writing instrument of FIG. 1 in an open condition;

FIG. 10 is an exploded side view of the writing instrument of FIG. 1 in an open condition, the opposite side being a mirror image thereof;

FIG. 11 is an exploded front view of the writing instrument of FIG. 1 in an open condition;

FIG. 12 is an exploded rear view of the writing instrument of FIG. 1 in an open condition;

FIG. 13 is a top plan view of the writing instrument of FIG. 1 in an open condition; and,

FIG. 14 is a bottom plan view of the writing instrument and cap of FIG. 1 in an open condition.

The dashed lines are for illustrative purposes only and form no part of the claimed design.
